UNITED STATES PATENT OFFICE.

WILLIAM W. BROWN, OF OAK LANE, PENNSYLVANIA, ASSIGNOR, BY MESNE ASSIGNMENTS, TO H. W. BUTTERWORTH & SONS COMPANY.

DRIVE MECHANISM FOR DYEING MACHINES.

Application filed February 14, 1924. Serial No. 692,743.

This invention relates to improvements in dyeing machinery and more particularly in some of its features to improvements in drive mechanism for dyeing machines of the rotary reel type.

It is a general object of the invention to improve and perfect dyeing machines of the class mentioned and drive mechanism therefore, so as to provide a simple, efficient and 10 sturdy construction which is economical from standpoints of production and operation.

A further object is the provision, for machines of the class mentioned, of an improved 15 unitary self-contained power transmission mechanism which is easily placed in position or removed, and the parts whereof are readily accessible for inspection, repair, adjustment, etc.

20 A further object is the provision of an improved drive mechanism for machines of the class mentioned and having an improved manual drive associated therewith for adjustment of the machine through a comparatively limited range when the power drive is inoperative.

A further object is the provision of an improved unitary power transmitting gear box for laundry machines or the like.

30 Other objects will be in part pointed out in connection with the following detailed description of an illustrative but preferred embodiment of the invention and will be in part obvious in connection therewith.

35 The invention accordingly comprises the features of construction, combination of elements, and arrangement of parts, which will be exemplified in the construction herein-after set forth and the scope of the application of which will be indicated in the 40 claims.

For a complete understanding of the nature and objects of the invention reference is had to the following detailed description, 45 and to the accompanying drawings illustrating a preferred embodiment, and in which:

Figure 1 is an end elevation of a dyeing machine embodying the improvements of the invention;

50 Fig. 2 is a central vertical longitudinal section;

Fig. 3 is a detail sectional view taken on the line 3-3 of Fig. 1;

55 Fig. 4 is a fragmentary detail section on the line 4-4 of Fig. 1;

Fig. 5 is an enlarged vertical section on the plane indicated by the line 5-5 of Fig. 1; and

Fig. 6 is an enlarged vertical section on the plane indicated by the line 6-6 of Fig. 1.

Referring to the drawing for a detailed description of the embodiment of the invention there shown, the dyeing machine includes a dye tank 10 and an inner rotatable receiving drum or reel 11 which is arranged 60 for reception of the goods under treatment. The tank is preferably provided with supporting end frames 12 and 13 having flat inner faces and flanged outer faces, downwardly extending pedestals 14 being preferably integrally secured to the frames. Each frame has a marginal frame member including a bottom member 15, side members 16 and top member 17 forming a substantially continuous perimetrical frame part. Intermediate the side frame members are spaced 70 upright frame members 18 and a horizontal member 19 extending between the spaced upright members and integrally connected therewith. The horizontal frame member 75 19 affords a brace between the upright members and may be continued to connect with one or more of the upright side members; it also provides a support for parts of the driving mechanism. All the frame members are 80 preferably cast as an integral unit and are provided with horizontal rigidifying flanges which may be continued around the pedestal 85 14 as shown. The end frames have flat smooth inner faces for the purpose of providing a seat for supporting end plates 20, and they are supported in spaced relation by means of tie rods 21. The bottom plate 22 is flanged outwardly marginally as indicated at 23 and connected by welding or by 90 bolts 24, or both, to outwardly protruding edges of the end plates 20 so as to provide liquid proof joints. The bottom plate is preferably continued upwardly to form the sides of the tank. The top of the tank is 95 closed by the cover 25 hinged to a longitudinal rod 26 carried by brackets 27 on the end frames. It will be noted that the inner smooth surfaces of the end frames provide a firm back support or seat for the end plates 100 while the rigidifying flanges for the frames are provided on the outer faces. The end frame supporting the driving connections is also provided with supporting blocks as 28 105 for attachment of the driving parts to the 110

end frame; these blocks may be formed integrally with the respective frame members, or made as separate parts.

The reel is mounted for rotation within 5 the tank, being supported at one end by means of a trunnion seated within an open top bearing 29 supported by the end frame 13, and at the opposite end by means of a supporting trunnion shaft 30 which is re- 10 movably but non-rotatably seated in the end or trunnion plate of the reel. The shaft 30 not only provides the driving connection for the reel but supports it upon the gear box as more fully pointed out below. An inlet pipe 15 31 is provided for the introduction of dye liquid and a drain outlet is provided at 32. Heating fluid, such as steam, may be introduced through a nozzle 33 shown as disposed near the bottom of the tank.

20 For driving the reel in carrying out the dyeing process, power transmission connections are provided including a gear train housed within a gear casing 34 and forming a unitary drive mechanism or gear box for 25 transmitting power from a driving motor 35 to the rotary reel. This casing is provided with lugs 36 for attachment to the end frame, being arranged for seating against the blocks 28 as shown. The gear casing is 30 provided with a removable cover so the interior space may contain lubricant for the interior operating parts. Mounted upon studs carried by the rear wall of the gear casing are spur gears 38, 39, and a toothed 35 sector 40 connected to a pin on the gear 39 by means of a pitman 41. The toothed sector meshes with a pinion 42 which is preferably integral with the driving shaft 30, the latter being carried in bearing supports in 40 the casing walls. A worm wheel 43 also supported by one of said studs and secured to the gear 38 for rotation therewith, meshes with a worm 44 carried by a shaft 45 mounted in oil-tight bearings in the casing walls 45 as particularly shown in Fig. 3.

As shown in Fig. 3 the worm shaft 45 extends from the casing at one end to which is attached a hand operating wheel 46, and at the other end for connection to a driving 50 gear 47 preferably mounted in a casing 48 carried by the end frame 12 through the attaching block 28 and arranged to be driven by a pinion 49 on the motor shaft. It will be observed (Fig. 1) that the motor 35 is 55 mounted on a lower integral enlargement of the upright frame member 18 and is wired for control by a snap switch mounted on the upper part of the end frame.

Referring more particularly to Figs. 2 and 60 6, it will be seen that the gear casing is provided with a projection 50 forming a casing or sleeve for the driving shaft 30. This sleeve is arranged to abut at its outer end with the end plate 20 of the tank and a 65 flanged threaded collar 51 surrounding the

shaft is arranged to be set up tightly to press the end plate firmly against the end of the sleeve so as to make a tight joint. Packing washers may be introduced if desired for insuring tight connections at this point. 70 This sleeve is also provided with interior packing 52 surrounding the shaft and held resiliently but firmly in place by a spring 53 housed within the sleeve. The purpose of the packing 52 is to provide an oil proof 75 joint for preventing seepage of the oil at this point and to prevent escape of the liquor from the tank. It will be noted that the drive shaft 30 traverses the end plate 20 and the sleeve 50 abuts the same at a point 80 spaced from the frame members whereby the end plate is yieldable inwardly or outwardly to compensate for slight displacements of the gear box so precise positioning thereof is unnecessary. It will also be noticed that the shaft 30 is removable when the casing cover 37 is removed thus facilitating removal of the reel, and furthermore that the reel is supported directly upon the gear casing through this shaft. As clearly 85 shown in Fig. 6, the shaft 30 may extend into bearing relation with the cover plate 37 which for this purpose is provided with a supporting bearing, and this contact of the shaft with the cover together with the contact provided by the side faces of the driving pinion 42, limits longitudinal displacement of the shaft 30. 95

From the foregoing it will be clear that the reel is given a reciprocatory rotary motion through the gear train described when the motor is set in operation. Due to the irreversible driving gear train provided by the worm 44 and cooperating worm wheel 43 as described, it would be difficult or impossible to turn the reel by direct application of turning force or moment thereto to bring it into proper position for reception or removal of goods. However the hand wheel 46 connected directly to the worm 100 shaft offers a convenient means for accomplishment of this adjustment through relatively small angles when the motor is inactive. This irreversible driving mechanism prevents accidental turning of the drum as 105 for example during loading or unloading when there may be considerable unbalance, particularly in cases where the drum includes a plurality of charge receiving compartments. Furthermore an important 110 consideration resides in the fact that the complete gear box forms a power transmission unit which may be removed or replaced in position as desired facilitating repairs, 115 replacements, etc. When the gear box is secured in position as shown, the worm shaft 45 is properly positioned for connection to the intermediate gear 47, and the pinion driving shaft 30 is in position for seating 120 in the trunnion plate of the reel. Operation 125 130

of the gear train is not interrupted by removal of the gear casing cover 37 thus permitting inspection of the parts when in operation.

5 Since certain changes may be made in the above construction and different embodiments of the invention could be made without departing from the scope thereof, it is intended that all matter contained in the 10 above description or shown in the accompanying drawing shall be interpreted as illustrative and not in a limiting sense.

It is also to be understood that the following claims are intended to cover all of 15 the generic and specific features of the invention herein described, and all statements of the scope of the invention which, as a matter of language, might be said to fall therebetween.

20 Having described my invention, what I claim as new and desire to secure by Letters Patent, is:

1. In a machine of the character described, in combination, a receiving reel, a frame for 25 rotatably mounting said reel, a power transmission gear box having a gear train for transmitting power from a source to said reel and including a worm shaft mounted in the gear box, said gear box forming a self-contained unit removable from or attachable to said frame as a unit, said worm shaft having extensions at opposite ends external of the gear box, one of said worm shaft extensions being positioned for connection to a 30 source of power and the other of said extensions having a manual operating member for adjusting said reel when the power drive is inactive.

2. In a machine of the character described, 40 in combination, a receiving reel, a frame for rotatably mounting said reel, a power transmission gear box with a casing having a removable cover, a gear train having gear train members for transmitting power from a 45 source to said reel and being mounted for operation in said casing independently of presence or absence of said cover, said gear box forming a self-contained unit removable from or attachable to said frame as a unit, and a trunnion shaft mounted in said casing 50 and connected to said gear train and contacting at its outer end with said casing cover.

3. In a machine of the character described, 55 in combination, a receiving reel, a frame for rotatably mounting said reel, a power transmission gear box with a casing having a removable cover, a gear train having gear train members for transmitting power from a source to said reel and being mounted for operation in said casing independently of presence or absence of said cover, said gear box forming a self-contained unit removable from and attachable to said frame as a unit, and a trunnion shaft mounted in said casing 65 and connected to said gear train and contact-

ing at its outer end with said casing cover, said gear train including a worm shaft having extensions at opposite ends external of the gear box one of said worm extensions being positioned for transmitting power from 70 a source and the other of said extensions having a manual operating member for adjusting the reel when the power drive is inactive.

4. In a machine of the character described, in combination, a tank having an end frame 75 with spaced frame members and a yieldable end plate lying on the inner side of said end frame, a receiving reel rotatably mounted within the tank, a power transmission gear box supported on the outer face of said 80 frame and having a gear train for transmitting power from a source to said reel, a driving shaft between said reel and gear box and supporting the former on the latter, and a casing for said driving shaft carried by said 85 gear box and having moisture tight connections with said yieldable plate at a point thereon intermediate said frame members, said gear box forming a self-contained unit removable from and attachable to said frame 90 as a unit.

5. In a machine of the character described, in combination, a tank having an end frame with spaced frame members and a yieldable end plate lying on the inner side of said end frame, a receiving reel rotatably mounted within the tank, a power transmission gear box supported on the outer face of said 95 frame and having a gear train including a worm shaft for transmitting power from a source to said reel, said power source being connected to the gear train through said worm shaft, a driving shaft between said reel and gear box and supporting the former on the latter, a casing for said driving shaft carried by said gear box and having moisture tight connections with said yieldable plate at a point thereon intermediate said frame members, said gear box forming a self-contained unit removable from and attachable 100 to said frame as a unit, and an operating member connected to the worm shaft of said gear train for manual operation of said reel when the power drive is inactive.

6. In a dyeing machine or the like, in combination, a tank having end frames and wall plates secured to the inner faces thereof, a reel within said tank, a bearing within said tank secured to one of said end frames for supporting one end of said reel, 115 a unitary gear box attached to the outside of one of said frames and having connections for transmitting power to said reel from a power source, said power transmitting connections including a drive shaft extending through one of said wall plates and detachably connected to an end of said reel for supporting and driving the same, said gear box having a detachable cover and providing a 120 housing entirely enclosing said power trans- 130

mitting connections, said drive shaft contacting at its outer end with said cover to retain the shaft against outward longitudinal movement, and an oil and moisture proof connection between said gear box and wall plate and surrounding said drive shaft.

7. In a dyeing machine or the like, in combination, a tank having end frames and wall plates secured to the inner faces thereof, a reel within said tank, a bearing within said tank secured to one of said end frames for supporting one end of said reel, a unitary gear box attached to the outside of one of said frames and having connections for transmitting power to said reel from a power source, said power transmitting connections including a drive shaft extending through one of said wall plates and detachably connected to an end of said reel for supporting and driving the same, said gear box having a detachable cover and providing a housing entirely enclosing said power transmitting connections, said drive shaft contacting at its outer end with said cover to retain the shaft against outward longitudinal movement, and an oil and moisture proof connection between said gear box and wall plate and surrounding said drive shaft, said gear box with its power transmission connections forming a self-contained structure adapted to be removed or placed in operative position as a unit.

8. In a drive mechanism for textile treating machinery, the combination with a rotary reel and a driving motor, of a gear train between said reel and motor including a worm and worm wheel whereby the gear train is irreversible through turning moment applied to said reel, and a hand operating member connected to said worm to move the reel when the motor is inactive.

9. In a drive mechanism for textile treating machinery, the combination with a rotary reel and a driving motor, of a gear train between said reel and motor including a worm and worm wheel, a hand operating member connected to said worm to move the reel when the motor is inactive, and connections between said worm wheel and the reel including a pitman rod and a toothed sector for transmitting oscillatory movement to the reel.

10. In a drive mechanism for textile treating machinery, the combination with a rotary reel and a driving motor, of a unitary gear box having mounted therein a driving gear train including a worm and worm wheel whereby the gear train is irreversible through turning moment applied to said reel, an extending worm shaft adapted for connection to said motor, said gear box also having a shaft adapted for supporting connection to the rotary reel and being attachable in position on the machine as a unit for power connection with the motor and

reel, and a hand operating member connected to said worm shaft for operating said reel when said motor is inactive.

11. In a dyeing machine, in combination, a tank having an end frame with frame members having smooth inner and flanged outer faces, a tank wall plate in supporting contact with said inner smooth faces and having a laterally flexible part spaced in the plane thereof from the said frame members, attaching blocks upon said flanged faces, a power transmission unit including a gear train and a casing for entirely enclosing said gear train for operation in an oil bath, lugs on said casing for attaching it in operative position on the end frame and positioned to contact with said attaching blocks, a rotary receiver drum within said tank, and a supporting and driving trunnion shaft for said drum mounted in said gear train casing and extending through said wall plate at said laterally flexible part thereof.

12. In a textile treating machine, in combination, a power transmission unit attached to the end frame of the machine and including a gear train and a casing entirely enclosing said gear train, said transmission unit being removable as a unit from operative position on the end frame, supporting studs for members of said gear train supported at one end by said casing and having opposite free ends, and a cover plate overlying the free ends of said studs and being removable without disturbing the operative relation of said gear train.

13. In a textile treating machine, in combination, a power transmission unit attached to the end frame of the machine and including a gear train and a casing entirely enclosing said gear train, said transmission unit being removable as a unit from operative position on the end frame, an operating shaft carried by said gear train casing and extending within the tank of the machine, an oscillatory toothed sector included in said gear train for driving said operating shaft, and a pitman connected to said sector and to another member of said gear train for imparting oscillatory movement to said operating shaft.

14. In a textile treating machine, in combination, a power transmission unit attached to the end frame of the machine and including a gear train and a casing entirely enclosing said gear train, said transmission unit being removable as a unit from operative position on the end frame, an operating shaft carried by said gear train casing and extending within the tank of the machine, an oscillatory toothed sector included in said gear train for driving said operating shaft, a pitman connected to said sector and to another member of said gear train for imparting oscillatory movement to said sector, supporting studs for members of said gear

train supported at one end by said casing and having opposite free ends, and a cover plate overlying the free ends of said studs and being removable without disturbing the operative relation of said gear train.

15. In a textile treating machine, in combination, a power transmission unit attached to the end frame of the machine and including a gear train and a casing entirely enclosing said gear train, said transmission unit being removable as a unit from operative position on the end frame, an operating shaft carried by said gear train casing and extending within the tank of the machine, an os-

cillatory toothed sector included in said gear train for driving said operating shaft, a pitman connected to said sector and to another member of said gear train for imparting oscillatory movement to said sector, said gear train including a worm in mesh with a worm wheel, and a worm shaft rotatably mounted in said gear train casing and having an extension for driving connection to a motor and a second extension for hand operation of said worm.
